Attorney

UNITED STATES PATENT OFFICE.

CARL B. PARSONS, OF DETROIT, MICHIGAN.

CONCEALED HINGE.

1,276,404.

Specification of Letters Patent. Patented Aug. 20, 1918.

Application filed July 13, 1917. Serial No. 180,310.

To all whom it may concern:

Be it known that I, CARL B. PARSONS, a citizen of the United States, residing at Detroit, county of Wayne, State of Michigan, have invented a certain new and useful Improvement in Concealed Hinges, and declare the following to be a full, clear, and exact description of the same, such as will enable others skilled in the art to which it pertains to make and use the same, reference being had to the accompanying drawings, which form a part of this specification.

10 This invention relates to concealed hinges and has for its object a concealed hinge of very simple and cheap construction, yet effective to accomplish the purpose for which it was designed.

In the drawings,—

Figure 1 is a cross section of the hinge attached to the door post.

Fig. 2 is a similar view showing the hinge in the operation of opening.

Fig. 3 is a vertical section through the door post showing the hinge in elevation.

25 Fig. 4 is a rear elevation showing how the parts are disassembled.

The hinge comprises the curved arm *a* which is of reduced width toward the pin end. This reduced width of the arm allows 30 the lifting of the pin (as shown in Figs. 3 and 4) out of its hole in the rearwardly projecting web *b*. This web is an integral part of the plate *c* which is screwed to the door post. The way this is assembled is 35 shown in Figs. 3 and 4.

The customary way of making concealed hinges has been to have the usual plate that screws to the door post and then have a pin-

carrying plate that screws to the first mentioned plate that allows the disassembly of 40 the hinge by taking out this pin-carrying plate and the hinge arm.

It will be seen from the above description that I accomplish the same result by simply using a flat plate that has only the rearwardly projecting web *b* to carry the pin 45 and that the pin and arm may be disengaged from the same by simply swinging the door open and lifting the pin out.

One of the features of this hinge is the 50 forming of the plate with the curved outside surface *c'*, whose contour is in conformity with the curvature of the body. This does away with the necessity of filing off the edge of the hinge to conform to the body 55 lines.

What I claim is:

In a concealed hinge, the combination of a plate having a slot therein, a rearwardly projecting web extending from one edge 60 of said slot and provided with a socket, a hinged arm having a reduced outer portion and the rest of said arm being of a dimension to fill said slot, said arm having a pin 65 extending therefrom adapted to engage in the socket in said web, the parts being so arranged that when the hinge is turned to its open position the reduced portion of said arm shall be within said slot to permit of the passage of the pin therethrough and in the other positions, said arm shall engage 70 the edge of said slot to prevent the disengagement of said pin.

In testimony whereof, I sign this specification.

CARL B. PARSONS.
